UNITED STATES PATENT OFFICE.

WILLIAM C. CUTLER, OF NORTH GLENDALE, CALIFORNIA.

POCKET-CASE FOR CALLING-CARDS.

1,248,823.

Specification of Letters Patent. Patented Dec. 4, 1917.

Application filed January 23, 1917. Serial No. 144,078.

To all whom it may concern:

Be it known that I, WILLIAM C. CUTLER, a citizen of the United States, residing at North Glendale, in the county of Los Angeles and State of California, have invented new and useful Improvements in Pocket-Cases for Calling-Cards, of which the following is a specification.

My invention relates to improvements in pocket cases for calling cards; and the objects of my improvements are, to throw out one card at a time while the case opens automatically; to provide operating means which can be disposed into ready made card cases without having to change such card case; to provide a throw which can be disposed in a ready made card case operating by the automatically opening of the top of such card case; the invention consisting in the construction, combination and arrangement of devices hereafter more fully described and claimed, and illustrated in the accompanying drawing, in which—

Figure 1 is a vertical section of my device. Fig. 2 is a section on line 2—2 of Fig. 1, the shifting means pushed in.

Fig. 3 is a similar section, the top of the case beginning to open and thereby tilting the shifting means ready to throw out a card if such were disposed in the case.

Fig. 4 is a horizontal cross section on line 4—4 of Figs. 1 and 3.

Similar numbers refer to similar parts throughout the papers.

The card case comprises a body part 1 and the top part 2, hingedly connected at 3. An engaging member or lock 4 is attached to the lower or body part of the case as indicated at 5. A push button 6 is disposed between the engaging member 4 and the case projecting through the case toward the outside. The end 7 of the engaging member is formed to engage with the lug or reinforcement 8 provided on the top or cover part 2 of the case.

A plate 9 is removably disposed in the lower or body part of the case having a slot 10 and the two bent edges 11 and 12. A spring 13 is placed between the bent edge 11 and the wall of the case extending with the upper end 14 into the top part of the case formed to open the top or cover whenever the cover is released by the push-button 6 from the engaging member 4.

Slidably mounted in the slot 10 of the plate 9 is a shifting bar 15, which is pointed

at the top end 16 to engage with cards when such are disposed in the case. The lower end 17 is bent projecting through the slot and is also provided with lugs 18 engaging behind the plate 9 preventing the shifting bar from falling out of the slot. An extension end 19 is formed on the bent end 17 of the shifting bar forming the pivot for connecting an operating rod 20 to the shifting bar. The operating rod 20, being pivotally connected by the extension end 19 of the shifting bar with the lower end, is also pivotally connected with the upper end to the cover 2 of the case as indicated at 21.

The cards are disposed in the compartment between the plate 9 and the outer wall 22 of the case, see Fig. 2, the space formed between the plate 9 and the outer wall 23 being used for the operating mechanism and spring.

Having filled the case with calling cards, a push on the button 6 releases the top 2, and the spring 13 with the top end 14 turns the top over to the position shown in dotted lines as indicated at 24, the operating rod 20 being attached to the top at 21 naturally pulls on the extension end 19 of the shifting bar 15 thereby tilting the shifting bar to the position illustrated in Fig. 3, and, as the pointed end 16 comes then into touch with the one card in the case nearest to the pointed end 16, this card is shifted out of the case to a suitable extent to be taken as the operating rod is lifted to such an extent by being attached to the top at 21, as will be understood from Fig. 1, the pivot 21 on the closed cover moving up to the position indicated in dotted lines on the opened cover.

Having taken that one card, the cover can be pressed down to the closed position, automatically pushing back the shifting bar 15, this not even scratching the cards in the case as the operating rod 20 naturally tilts the shifting bar to the position shown in Fig. 2 within the slot of the plate 9 and the shifting bar moves to the starting position within the slot of the plate 9.

A slot 24 is provided in the top 2 of the case, allowing the cards to move upwardly before the top is entirely opened, as I prefer to have the case in about the size to inclose the cards without leaving much space within the case between the cards and the lid of the case. When opening the case, however, such construction would naturally cause the cards to press against the lid near

the hingedly connected end of the lid if no slot had been provided in the lid, and the cards, not being able to move as much or as quickly as the shifting bar 15, which is connected to the front end of the lid by the operating rod 20, would naturally be spoiled by the pointed end 16, engaging with the cards. This also allows the taking out of cards without having to open the card case 10 fully, as one corner of the shifted card naturally points out of the card case through the slot after a short movement of the card shifting means, when the card may be taken out of the case by hand, through the slot.

15 A spring 25 is provided inside of the case bringing the cards close to the card-shifting means and below the slot 24 in the top. Having thus described my invention, I claim:

20 1. In a card case of the type described a plate having the longitudinal edges bent forming engaging members for removably fitting into the card case and having also a slot longitudinally in the plate, and card 25 throwing means slidingly mounted for tilting movement in combination with the sliding movement in the slot of the plate, the said plate being spaced from one side of the case by the bent edges for inclosing the card 30 throwing means forming a card protecting member preventing a spoiling of the cards by the card throwing means.

35 2. In a card case of the type described a plate having the longitudinal edges bent forming engaging members for removably fitting into the card case and having also a slot longitudinally in the plate, a card shifting bar slidingly fitting in the slot projecting toward the cards when such are inserted in the case having means slidingly engaging with the plate and having also means for tilting the shifting bar toward the cards in the case, and operating means engaging with the card shifting means and the lid 40 of the case.

45 3. In a card case of the type described a plate having the longitudinal edges bent forming engaging members for removably fitting into the card case and having also a slot longitudinally in the plate, card shifting means slidily and tiltingly mounted in the slot, and a spring inserted between the bent edges of the plate and the case thereby locking the plate in the case.

50 55 4. In a card case of the type described a plate having two edges parallel to each other bent forming spacing and engaging members and having also a slot in the plate parallel to the bent edges, a spring inserted between one of the bent edges and the case for holding the plate in a fixed position, and card shifting means slidily and tiltingly mounted in the slot in the plate and having means for automatically operating the card 60 65 shifting means when opening the case.

5. In a card case comprising a body member, a top member and a locking means, a plate having two edges parallel to each other bent forming spacing and engaging members and having also a slot in the plate parallel to the bent edges, a spring inserted between one of the bent edges and the body member forming the engaging means by which the plate is held in a fixed position in the body member and forming also the 70 spring for automatically opening the case when releasing the top member from the body member by suitable locking means on such cases, a card shifting bar slidily mounted in the slot of the plate having a 80 pointed end projecting into the space in the case provided for the cards and having engaging members on the other end of the shifting bar disposed in the space formed by the spacing members on the plate slidily engaging with the plate, and operating means disposed in the space formed by the spacing members engaging with the shifting bar and the case top member.

6. In a card case of the type described a 90 plate removably engaging within the body member of the case having a slot formed therein, a card shifting bar slidily and tiltingly mounted in the slot of the plate having engaging means formed on the free 95 end projecting toward the cards when such are disposed in such cases, operating means connected to the card shifting bar with one end and to the top member of the case with the other end normally holding the engaging 100 member of the card shifting bar disengaged from the cards in such cases, the shifting bar being slidily held on the lower end while the free upper end with the card engaging means forms the gravity means by 105 which the card shifting bar is caused to fall with the card engaging means toward the cards when released by the operating means when the card case is opened.

7. In a card case comprising a body member and a top member hingedly connected to the body member having also a locking means opposite to the hinge, a plate removably disposed in the body member of the case, the plate having a slot in the direction 110 toward the opening of the case, a card shifting member of the width of the slot in the plate slidily fitting with the longitudinal edges within the slot, the upper end of the card shifting member terminating in a 115 pointed end for engaging with the cards disposed in the case, the lower end of the card shifting member being bent projecting behind the plate, lugs being formed on the longitudinal edges of the bent lower end 120 engaging behind the plate preventing the card shifting member from disengaging from the plate, the bent end of the card shifting member terminating in a pin, and an operating rod engaging with one end with the 125 130

pin on the bent end of the card shifting member and the rod engaging also pivotally with the other end with the top member of the case.

5 8. In a card case comprising a body member and a top member, a plate having means removably engaging within the body member of the case having also a slot provided therein, a card shifting bar fitting with its 10 longitudinal edges slidingly in the slot having means on one end slidingly engaging with the plate while the long free end of the card shifting bar is formed narrower allowing a tilting of this end toward the cards 15 when such are inserted into the case, and operating means connected to the card shifting bar and the top member of the case.

9. In a card case comprising a body member and a top member, a plate having means removably engaging within the body member of the case having also a slot provided therein, a card shifting bar fitting with its longitudinal edges slidingly in the slot having two lugs formed on one end engaging 20 slidingly behind the plate and having also a short extension end beyond the engaging 25

lugs, the main part of the shifting bar forming a tilting member having a pointed end projecting toward the cards when such are disposed in the case, and an operating bar 30 connected to the short extension end of the shifting bar with one end and with the other end to the top member of the case.

10. In a card case comprising a body member and a top member, a plate fitting in the 35 body member of the case, card shifting means slidingly mounted on the plate, operating means connected to the card shifting means and to the top member of the case, and a spring secured inside of the case opposite to the card shifting means and the plate, the top member being provided with a slot 40 in a position to allow the card thrown out of the case by the shifting means to slip out of the case through the top member before 45 the top member is entirely opened.

In testimony whereof I hereunto affix my signature in the presence of two witnesses.

WILLIAM C. CUTLER.
